UNITED STATES PATENT OFFICE.

RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

BLUE-FLAME OIL-BURNER.

1,202,523.

Specification of Letters Patent. Patented Oct. 24, 1916.

Application filed July 3, 1916. Serial No. 107,274.

To all whom it may concern:

Be it known that I, RUDOLPH HOFFMAN, a citizen of the United States, residing at Kankakee, in the county of Kankakee and 5 State of Illinois, have invented certain new and useful Improvements in Blue-Flame Oil-Burners, of which the following is a specification.

This invention relates more particularly 10 to improvements in the type of burner shown in Patent No. 1,092,262, granted April 7, 1914, the features of improvements being pointed out hereinafter.

In the accompanying drawings, Figure 1 15 is a fragmental vertical central section through a burner embodying the features of my invention. Fig. 2 is a top plan view of the inner air controller.

The body 1 of the burner comprises an inner wick tube 2 and an outer wick tube 3, said tubes forming an annular space to contain a wick 4. In the construction herein 20 illustrated, the outer wick tube terminates in a horizontal plane slightly below the 25 plane of the top of the inner wick tube, and the upper ends of the wick tubes are preferably bent inwardly slightly, as shown. Air is admitted to the inner and outer sides of the annular flame produced by the wick, the 30 air being controlled by an inner air controller and an outer air controller.

The inner air controller 5 is herein shown 35 as loosely supported concentrically with the wick tubes upon a cupped member or ring 8, said ring being supported within the body 1 by means of a spider 9. The spider 9 may, if desired, be formed of two sheet-metal 40 cross-bars intersecting each other at right angles, the ends of said bars being secured to the inner wick tube by means of solder or in any other suitable manner. In order 45 to maintain the true circular form of the inner wick tube 2, I provide a ring 2^a fitting tightly within and extending trans- versely of said wick tube. The ring 2^a extends through slots 9^a in the spider 9. The member 8 has an outwardly extending 50 annular flange 8^a which causes the air current to flow upwardly close to the inner wick tube, said air current carrying up any vapors which might otherwise flow down and condense on said tube. In the cupped member 8 and in the lower end of the air controller 5 are registering openings 8^b and 5^b, respectively. The air controller 5 comprises a

body 5^a which, in the present embodiment of the invention, has a flat upper side formed by a perforated disk 7 that extends transversely of the body. The largest diameter of the body 5^a is in the plane of its upper side, and is located approximately in the plane of the upper end of the inner wick tube.

Above and spaced away from the disk 7 is a disk 10. In the construction herein shown by way of example, the outer portions of the disk 10 are spaced away from the disk 7 by downwardly extending lugs 11 stamped from the disk 10. Above the disk 10 is another disk 12, said disks being so formed that a space is provided between them, as shown.

While the disks 7, 10 and 12 may be secured in place in any suitable way, I have herein shown a screw 13 extending through 75 said disks and through a circular concave plate 14, spacing thimbles 15 and 16 being located at opposite sides of the disk 7. 17 is a nut turned on the lower end of the screw 13. The disk 7 and the plate 14 are 80 clamped to the body of the air controller 5 by an annular flange 18. The plate 14 has air openings 19. The openings 20 formed in the disk 10 by the punching down of the lugs 11 admit air to the space between the 85 disks 10 and 12.

In use, air is supplied to the inner side of the annular flame through the space between the inner wick tube and the air controller, through the space between the disks 7 and 10, and through the space between the disks 10 and 12. I do not, however, attribute particular importance to the air supplied through the last mentioned space. The disks 10 and 12 cause the blue flame to be 95 longer than it otherwise would be.

The outer air controller may be of any suitable construction. In the present drawings is shown a controller similar to the one fully illustrated and described in my co-pending application Serial No. 912, filed January 7, 1915, (Patent No. 1,188,780, dated June 27, 1916).

I claim as my invention:

1. A blue-flame burner having, in combination, an annular wick container and an air controller within the wick container, said controller comprising a body, a perforated disk extending across the upper portion of the body approximately in the plane 110

of the upper end of the wick container, a 45
perforated securing plate within the body
below said disk, a pair of disks above and
concentric with the perforated disk and the
5 securing plate, spacing devices between the
pair of disks and the perforated disk and
between the perforated disk and the securing
plate, and a securing device connecting
said disks and plate, the lower end of the
10 body having an air inlet opening.

2. A blue-flame burner having, in combi- 50
nation, an annular wick container and an air
controller within the wick container, said
controller comprising a body, a perforated
15 disk extending across the upper portion of
the body, a perforated securing plate within
the body below said disk, a disk above and
concentric with the perforated disk and the
securing plate, spacing devices between the
20 second mentioned disk and the perforated
disk and between the perforated disk and the
securing plate, and a securing device connect-
ing said disks and plate, the lower end of the
body having an air inlet opening.

25 3. A blue-flame burner having, in combi- 55
nation, an annular wick container and an air
controller within the wick container, said
controller comprising a body, a perforated
disk extending across the upper portion of
30 the body approximately in the plane of the
upper end of the wick container, a pair of
disks above and concentric with the perfor-
ated disk, spacing devices between the pair
of disks and the perforated disk, and means
35 connecting said disks to the body, the lower
end of the body having an air inlet opening.

4. A blue-flame burner having, in combi- 60
nation, an annular wick container and an air
controller within the wick container, said
controller comprising a body having a flat
40 upper side located approximately in the
plane of the upper end of the wick con-
tainer, and a plate concentric with and
spaced away from and above the body, the
lower end of the body having an air inlet opening.

45 spaced away from and above the body, the
lower end of the body having an opening to
permit air to flow upwardly through the
body and outwardly through the space be-
tween the body and said disk.

5. A blue-flame burner having, in combi- 50
nation, an annular wick container and an air
controller within the wick container, said
controller comprising a body having its
largest diameter located approximately in
the plane of the upper end of the wick con-
55 tainer, a perforated disk extending entirely
across the body in approximately said plane,
and a disk located above and concentric with
said perforated disk, the lower end of the
body having an opening to admit air.

6. A blue-flame burner having, in combi- 60
nation, an annular wick container and an air
controller within the wick container, said
controller comprising a body terminating
approximately in the plane of the upper end
65 of the wick container, the upper end of said
body being relatively close to the wick con-
tainer, and a disk located above said plane
and concentric with and spaced away from
the body, means being provided to permit
70 air to flow upwardly around and through
the body and outwardly through the space
between the body and the disk.

7. A blue-flame burner having, in combi- 75
nation, an annular wick container and an air
controller within the wick container, said
controller comprising a body, the upper end
of which body is of larger diameter than the
remainder of the body, said upper end being
located approximately in the plane of the
upper end of the wick container, and a disk
80 spaced away from and secured to the body
above and concentric with the body.

In testimony whereof, I have hereunto set
my hand.

RUDOLPH HOFFMAN.
